UNITED STATES PATENT OFFICE

1,927,706

CONTAINER

Everett I. House, Eveleth, Minn.

Application May 16, 1931. Serial No. 537,947

3 Claims. (Cl. 220—55)

The invention relates to improvements in containers and has reference more particularly to a safety cover for containers whereby the same are suitable, in addition to other uses, for transporting explosives.

The present invention has been illustrated as applied to a container of circular shape such as employed in fuse and cap boxes. Receptacles of this nature are used for transporting cut lengths of capped fuse from a central storehouse under ground to the working contracts, and it is especially desirable that the same be equipped with some form of safety fastening means for insuring, during transportation, that the cover will not become loose or detached from the body portion. Accordingly, it is contemplated to provide fasteners on the body and cover and pass through the same the carrying cord or strap by which the container is carried. When loose the cover can be removed for permitting removal of the contents, but when being transported the cord or strap holds the cover tightly closed and therefore forms an efficient and economical arrangement and one which is absolutely safe.

An object of the invention, therefore, is to provide containers or the like with fastening means for securely holding the cover in place, especially when the same is being transported and which will also permit the cover to be readily detached when desired.

An additional object is to provide securing means of the character described which will be simple in construction, inexpensive to manufacture and safe and efficient in operation.

With these and other objects in view, the invention may consist of certain novel features of construction and operation as will be more fully described and particularly pointed out in the specification, drawing and claims appended hereto.

In the drawing, which illustrates an embodiment of the device and wherein like reference characters are used to designate like parts—

Figure 1 is a perspective view of a container showing the same equipped with the device of the present invention.

Figure 2 is a front view of the container shown in Figure 1.

Figure 3 is a side elevational view of a container showing the means for maintaining the cover in engagement with the body portion.

Referring to the drawing, the present invention is disclosed as applied to a circular container or receptacle having a body portion 10 and a cover 12. On the body portion are pro-

vided a plurality of fastening elements or clips 14 located in spaced relation, preferably 120 degrees apart, and held to the body by rivets 16.

Similar fastening elements 18 are provided for the cover 12, the same being positioned diametrically opposite each other on a horizontal plane. A strap or cord 20, by means of which the container is carried, is passed through the lowermost clip 14 on the body and then the ends of the strap are passed through clips 18 on the cover and finally through the two uppermost clips on the body. The strap thus fastens the cover to the body portion in such a manner that it is removable when the strap is loosened, yet is correspondingly held in tight engagement with the body when the strap is tightened.

The present device has found extensive use with much success in mines and other places where caps and fuses are used in quantities, since by the above structure the cover is detachable but is held tightly closed when the container is being carried by the strap. Also the cover remains on the strap at all times and consequently can not be mislaid. The relation of the strap to the fasteners on the body and cover prevents the cover from accidentally falling off and the contents spilling on the ground through neglect to buckle a strap or similar form of fastening means with which containers have heretofore been provided.

It is to be understood that I do not wish to be limited by the exact embodiment of the device shown, which is merely by way of illustration and not limitation, as various and other forms of the device will of course be apparent to those skilled in the art without departing from the spirit of the invention or the scope of the claims.

I claim:

1. In a receptacle, a body portion having spaced clips thereon, a slip cover for the body portion also provided with spaced clips, said clips on the body being spaced and staggered with respect to the clips on the cover when the parts are in proper assembled relation, and a strap for carrying said receptacle, said strap being looped through the clips on the body portion and cover alternately, the spacing of the body clips with respect to the cover clips being sufficient to permit the cover to be removed from the body without withdrawing the strap from the clips.

2. In a receptacle, a body portion having clips spaced around the periphery thereof, a detachable cover for the body portion also provided

with spaced clips on its periphery, said clips on the body alternating with those on the cover when the parts are in assembled relation, and a strap passing through the clips on the body and 5 cover to retain the cover thereon and by which the receptacle may be carried, the spacing of the body clips with respect to the cover clips permitting the cover to be removed without withdrawing the strap from the clips.

10 3. In a cylindrical receptacle, a body portion having clips spaced around the periphery there-

of, a detachable cover for the body portion also having spaced clips around its periphery, and a strap passing through the clips on the body and cover alternately for holding the cover closed when the receptacle is being carried, the spacing of the clips with respect to each other being sufficient to permit removal of the cover by loosening of the strap and without withdrawing the strap from the clips.
